UNITED STATES PATENT OFFICE

HOWARD D. RANDALL, OF CINCINNATI, OHIO, ASSIGNOR TO THE RANDALL COMPANY,
OF CINCINNATI, OHIO, A CORPORATION OF OHIO

HOOD PAD

Application filed January 19, 1929. Serial No. 333,669.

This invention relates to an improvement in packing for hoods for radiators commonly called hood pads, and is especially adapted for motor cars.

5 One main object of this invention is to devise a method and construction of attachment for hood pads that will be suitable to the needs and requirements of the motor car manufacturer and user in the following respects:

First—The attachment must be such that the packing will be securely held against the metal edge of the radiator and that no two metal surfaces shall contact in order to avoid 15 the rattle that would otherwise occur.

Second—The method of attachment must be such that the parts can readily be secured without requiring special formations or depressions in the metal of the radiator, and it 20 is also desirable that the parts be capable of being readily disassembled.

Third—In order to eliminate any danger 25 of rattle the method of attachment should be such that all metal parts can be driven into engaging position thereby insuring the tightest fitting of those parts and simultaneously causing the head of the attaching means to be depressed within the hood packing, so as to preclude any and all contact of the metal 30 hood and said head.

To this end there is shown a two part metal attaching means and the specific method requires that one of these parts first be positioned so that it will temporarily secure the 35 fabric to the radiator edge, there being merely the requirement that sufficient frictional contact exist between the support and said attaching part to hold the packing in position on the radiator. This will only require that an opening be punched through the metal of the radiator of such size as to permit the shank or prongs of said member to be readily inserted into same. Thereafter the other member of the attaching means is 40 driven through the attached fabric and first mentioned attaching means in a way to force parts of said attached metal member into clamping relation with the radiator edge and simultaneously force the head of the driven 45 member into the fabric in a way to prevent 50

all possible contact between its head or the head of the other member with the metal of the hood or radiator. In order to bring about these desirable results, it is essential that the packing be positioned between the two attaching members and that the construction of parts be such that one attaching member can be driven into locking relation with the other member and the two locked members be likewise clamped to the radiator, 55 while simultaneously with this operation any exposed metal part of the attaching means will be forced into the packing forming thereby a depression in the fabric which will protect the parts from contact with the hood. 60 Furthermore, this construction and method permits the parts to be readily disassembled by driving the driven member out of its locking position. The packing material may consist of continuous strips or may be of the form 65 of independent washers placed at predetermined points on the radiator or cowl flange and is preferably two layers of fabric of different thickness.

Other objects and advantages will be in 70 part indicated in the following description and in part rendered apparent therefrom in connection with the annexed drawings.

To enable others skilled in the art so fully 75 to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:—

In the drawings Figure 1 is an elevational view showing the hood in open position. Fig. 2 is a plan view of one of the locking members secured to one layer of fabric, while Fig. 3 is a plan view of the completed locking device. Fig. 4 is a detail sectional view showing the first locking member in position on the flange of the radiator, while Figs. 5 and 6 are detail views showing the insertable locking member in its relation to the first mentioned locking member.

In the drawings the radiator of the ordinary motor car is indicated by 1, the radiator 100

and cowl flange thereof being indicated by 2. The hood or cover is 3 and the outer edge of the hood 3 (the edge nearest the radiator cap 4) overlaps the flange 2 of the radiator and 5 cowl and the cushioning pad 5 lies between the metal surfaces of said flange and that of the hood.

A cup shaped metal member 6 is inserted in the opening 7 (Figs. 2 and 4) perforating 10 the lower layer of fabric, which as heretofore explained may be shaped like a washer but is preferably shown as a strip of fabric. One end of said member, is formed in the shape of a cup which is thereby clamped as 15 hereinafter explained to said fabric 5, and the prongs 9 project through openings in the said flange 2 as indicated in Fig. 4. The insertable nail 10, which is the other locking member, is notched at 11 and this member 20 can be forced through a perforation in the upper layer of fabric which is preferably a chrome leather washer 12, and through the opening in the metal member 6. As clearly appears from Fig. 4 the cup shaped member 25 6 holds the lower layer of fabric in position while the other layer of fabric (see Fig. 5) is placed in position concealing and covering the first layer as well as the cup shaped member. The nail 10 is then driven into 30 position as shown in Fig. 6. The dimensions of the two members 6 and 10 are such that the notched end 11 of said second member will force the prongs 9 outwardly thereby automatically clinching the member 6 against the 35 underside of radiator and cowl flanges and the spring of the metal is such that the ends of the prongs will automatically engage the notches as shown in Fig. 6 and hold the nail in its final position. In this manner the 40 fabric will be securely clamped to the upper surface of the radiator and cowl flanges by the caps of the two locking members while the locking members will be locked to the inner surface of the radiator and cowl flanges 45 by reason of the clinching of the prongs 9 and the interengagement of the notched end 11 and the edges of member 9. As appears clearly in Fig. 6 the head of nail 10 can be depressed into the thin fabric 12 and can be 50 held rigidly in that position. The parts can be readily disassembled by driving the nail 10 out of locking position with said member 6, when replacements or repairs are needed, and as shown in Fig. 6 the cap of the nail 11 55 is sufficiently depressed to prevent the hood 3 contacting against it.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore such adaptations should 60 65

be, and are intended to be, comprehended within the meaning and range of equivalency of the following claims:—

Having thus revealed this invention, I claim as new and desire to secure the following combinations and elements, or equivalents thereof, by Letters Patent of United States:

1. In a device of the character described comprising a metal support and a metal cover the combination of a two part cushioning pad with a two part attaching device, the lower part or layer of the pad being first secured to said support, one part of said attaching device being cup shaped and 75 being capable of insertion through said lower layer and an opening in the support to hold said layer temporarily on said support, the other layer being positioned on top of said first layer and said attaching cup shaped 80 member, thereby concealing same, the other part of said attaching member being thereafter driven through both layers of fabric and into said cup shaped member, the upper 85 layer being depressed at the point of entrance of said driven member and the cup shaped member being automatically clamped to said driven member and to said support after the head of said driven member is positioned in the depressed part of said upper 90 layer of fabric, the two parts of the attaching device being capable of disengagement by driving said driven member out of contact with said cup shaped member.

2. The method of securing cushioning pads 100 between two metal members by first positioning one layer of fabric upon one of the metal members, a socket shaped metal member with prongs thereon being inserted through said fabric, the prongs extending through an 105 opening in the metal support, then positioning a second layer of fabric to cover and conceal said socket member and finally driving a second attaching member having a notched shank through said upper layer and into said 110 socket shaped member until the head of said driven member is depressed into the upper layer of fabric and the prongs engage said notched shank while the outer ends of said 115 prongs are clinched against the metal support.

3. The method of securing cushioning pads 120 between two metal members by first positioning a layer of fabric with a socket shaped member having prongs inserted through the fabric upon one of said members, the prongs also extending through an opening in the metal support, then positioning a second layer of fabric for covering and concealing said 125 socket member and finally driving a second attaching member having a notched shank through said upper layer and into said socket shaped member, the head of said second attaching member being smaller than the opening in said socket shaped member for 130

permitting the head to depress part of the upper layer of fabric within said socket shaped shank member, the prongs engaging said notched shaped member while the outer ends of the said prongs are clinched against the metal support.

In witness whereof, I have hereunto subscribed my name.

HOWARD D. RANDALL.
